UNITED STATES PATENT OFFICE.

CHARLES I. TENNEY, OF MASON CITY, IOWA, ASSIGNOR TO PRACTICAL GAS CONSTRUCTION COMPANY, OF NORTH CHICAGO, ILLINOIS, A CORPORATION OF ILLINOIS.

CARBURETER.

SPECIFICATION forming part of Letters Patent No. 714,414, dated November 25, 1902.

Application filed October 30, 1901. Serial No. 80,493. (No model.)

To all whom it may concern:

Be it known that I, CHARLES I. TENNEY, a citizen of the United States, residing at Mason City, in the county of Cerro Gordo and State 5 of Iowa, have invented a certain new and useful Improvement in Carbureters, of which the following is a specification.

This invention relates to apparatus for the production of illuminating-gas from gasolene 10 or analogous hydrocarbons; and the invention has for its object to increase the efficiency of this type of carbureters both in the quality of carbureted air produced and in the economy in the production of the same.

15 The nature of the invention is fully disclosed in the description and claims following, reference being had to the accompanying drawings, forming a part of the specification, in which—

20 Figure 1 is a diagrammatic view of apparatus embodying my invention. Fig. 2 is a section of the sprayer, and Fig. 3 is a section of the drier.

In the drawings, A designates a water-tank 25 or cistern, in which is mounted a bell B in the usual way. In the bottom of this tank is a carbureter C, communicating with the interior of the bell by a vertical air-pipe C'. Air is forced into this bell through a looped 30 pipe D, communicating with a blower (not shown) either directly or through an air-chamber E, which may connect with the pipe D by pipes E' and E''. By means of cocks D' and E'' the air may be conveyed through or 35 around the air-chamber, as desired. The purpose of this air-chamber is to take and absorb the pulsations of the blower, which otherwise are communicated to the service-mains and cause more or less flicker in the lights.

40 The gasolene or other suitable hydrocarbon is contained in bulk in a reservoir F, the bottom of which is lower than the bottom of the carbureter, but its top is higher. A pipe G leads from the lower part of the carbureter 45 to the lower part of the reservoir and is provided with a suitable stop-cock G', opened and closed by a long-stemmed wrench G''. The upper parts of the carbureter and reservoir are connected by a pipe H.

50 I is a supply-pipe for the reservoir.

J is a pump which is provided with a pair of suction-pipes K and K', provided with suitable cocks K² and K³, respectively. The pipe K extends to the bottom of the reservoir and serves for drawing out the heavier and poorer 55 gasolene, which naturally settles to the bottom of the reservoir. The other one terminates some distance from the bottom and is used to supply a small tank L, placed high enough so that a part of its contents may flow into a 60 sprayer-tank M. A pipe N connects the pump with the tank L and is provided with a stop-cock N'. A waste-pipe O also communicates with the pump and has a stop-cock O'. When it is desired to pump out waste mate- 65 rial, the cocks O' and K² are opened and the cocks N' and K³ are closed.

From the sprayer-tank a pipe P leads to the carbureter and serves as a conduit for the gas generated therein. To this pipe is connected a looped pipe Q, leading to the opposite end of the tank and provided with a cock Q'. By means of cocks P' and P'' the gas may be passed directly into the tank or carried around it to the other end and enter 75 through the spray-pipe R, connecting the chambers L and M.

S is a drain-pipe to carry the residuum of the sprayed gasolene down to the carbureter.

A simple form of spraying apparatus is 80 shown in Fig. 2. In this the gasolene-pipe R projects through an elbow Q² and inside the pipe Q. At the inner end of the pipe Q is set a cone T, whereby the commingled gas and gasolene are scattered in a fine spray inside 85 the chamber M. By this means the carbureted air after leaving the carbureter may be still further enriched if it shall be found wanting in hydrocarbon. On the other hand, if the carbureted air generated in the carbureter is 90 rich enough the sprayer may be cut out, as already explained, but without interfering with the feed of gasolene to the carbureter through the spraying-chamber.

The upper part of the spray-tank commu- 95 nicates by pipes U, provided with a suitable cock U', with a drier V, which is simply a closed receptacle filled with a suitable absorbent—such, for example, as coke or cotton. The pipe also connects with the inside main 100

W, which is provided with a stop-cock W'. A loop U² connects the drier with the main, and by means of the cocks U' and W' the carbureted air may be carried from the spray-
5 tank directly to the main or through the drier, as circumstances may require. The carbureted air passes to a gasometer X and thence to the outside or service main in the usual way.

10 The gasometer-bell may connect by a chain Y, passing over sheaves Z, with the lever of the stop-cock R', and thus the flow of gaso-
lene through the spray-pipe be automatically shut off whenever the bell reaches a certain
15 elevation.

The proper level of gasolene in the chamber L is ascertained by means of a gage-glass L'.

It will be observed that after gasolene has been pumped to the desired level in the re-
20 ceiving-chamber L and the various cocks have been properly adjusted the action of the apparatus is automatic, the blower supplying air by which gasolene is vaporized in the carbureter and the spraying apparatus supply-
25 ing new gasolene for what is consumed.

It is to be noticed that the construction is such that only good gasolene can be used in the carbureter, the heavy and gummy material all being drawn away from time to time
30 from the bottom of the reservoir.

I have called the tank B a "compressed-air" tank and the tank E a "pulsation-reducer," for such is its function. It is placed in the circuit between the source of supply of com-
35 pressed air and the compressed-air tank, though the connections are such that it may be cut out of this circuit.

I claim—

1. In a carbureter spraying device, the com-
40 bination of a tank with a pipe-opening therein at each end, a looped pipe about the same, a gas-supply opening into the pipe at one end and into the loop at the same end, said loop opening into the pipe which opens into the
45 spraying device at the other end, a hydro-
carbon-supply pipe opening into the second pipe which leads into the sprayer, and suitable valves whereby the gas can be passed through the loop and mingled with the hy-
50 drocarbon or can be passed directly into the sprayer.

2. In a machine for carbureting, the com-
bination of a carbureter with a reservoir for

holding gasolene, arranged so as to extend vertically partly below and partly above the 55 level of the carbureter, with pipes connect-
ing the upper and lower parts of the carbureter and reservoir respectively, a spraying-chamber and a sprayer therefor, a receiving-chamber to receive gasolene, and connections 60 whereby the gasolene may flow thence into the spraying-chamber, pipes connecting the carbureter with the sprayer and the sprayer with the receiver for gasolene, and means for supplying said receiver from the reservoir 65 substantially as set forth.

3. In a machine for carbureting, the combination with a carbureter and means for sup-
plying air thereto under pressure, of a spray-
ing-chamber, a gasolene-receiver adjacent 70 thereto and a connecting-pipe provided with spraying apparatus, a pipe leading from the bottom of the spraying-chamber to the carbureter, a pipe leading from the said cham-
ber at a higher level to the carbureter, a pipe 75 leading from said higher pipe around the spraying-chamber and connecting with the spray-pipe, and cocks to regulate the flow of gas and gasolene, whereby the gas from the carbureter may be conducted direct to the 80 spraying-chamber, or through the sprayer into said chamber, and the surplus gasolene may be conducted to the carbureter, as de-
scribed.

4. In a machine for carbureting, the com-
bination with a carbureter and means for sup-
plying the same with air under pressure, of a reservoir for gasolene extending both above and below the levels of the top and bottom of the carbureter, pipes connecting the upper 90 and lower portions of the carbureter and said reservoir, respectively, a stop-cock for the lower pipe, a pump provided with two suc-
tion-pipes, one extending to the bottom of the reservoir and the other to some distance 95 above said bottom, cocks therefor, a receiver for gasolene as pumped from the reservoir, a pipe connecting said receiver with the pump and a cock therefor, a sprayer, and pipes connect-
ing the receiver with the sprayer, and 100 the sprayer with the carbureter, substantially as and for the purposes set forth.

CHARLES I. TENNEY.
